UNITED STATES PATENT OFFICE.

ALONZO PAWLING, OF MILWAUKEE, WISCONSIN.

TOOL-HOLDER.

SPECIFICATION forming part of Letters Patent No. 319,016, dated June 2, 1885.

Application filed November 24, 1884. (No model.)

To all whom it may concern:

Be it known that I, ALONZO PAWLING, a citizen of the United States, residing at Milwaukee, in the county of Milwaukee and State 5 of Wisconsin, have invented certain new and useful Improvements in Turning-Tool Holders; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention, to be hereinafter claimed, relates to improvements in metal-turning-tool holders. The object of my invention is to provide a simple, easily-adjusted, and unyielding holder for the cutting-tool.

20 To aid me in my description and for a more ready and full understanding of my invention, reference is hereby made to the accompanying drawings, in which—

25 Figure 1 is a perspective view of the stock, tool, and co-working parts of my invention. Fig. 2 is the key, and Fig. 3 is a front end view of the holder.

30 A is the stock, provided near its front end with an aperture at an angle to its long axis, and also preferably at a slight angle to its perpendicular axis, (as shown in Fig. 3,) for the reception of the cutting-tool B. The cutting-tool B has across its long axis, on its side that is to the rear when adjusted in the holder, a 35 series of recesses or notches, c. The stock A has an intercepting aperture extending from the aperture adapted for the reception of the cutting-tool B to the rear end of the stock, which aperture is adapted for the reception of 40 the key C and bolt D, and has cut in its rear part a female screw-thread adapted for the reception of the screw cut on the bolt D, and said bolt has a square head, d, or other equivalent means of turning it. The key C has a 45 slight forward and backward movement in the aperture in the stock nearly at right angles

with the axis of the tool, and is preferably provided with a short recess or slot, b, into which is inserted through the side of the stock the retaining pin or screw a, adapted to hold the 50 key in position, but permitting the movement described. The front end of the key C is beveled or otherwise made to fit into the recesses in the back of the cutting-tool B, and this key is of such length as to extend from the 55 cutting-tool to and against the front end of the bolt D. It will be seen that, the parts of this device being in position, by tightening the bolt D the key C will be forced firmly into a recess on the tool B, thereby holding the tool 60 rigidly in the stock against the force applied at its outer front end, and by unscrewing the bolt D and turning the stock upright the key C will by its gravity drop away from and release the tool B, whereby it can be re- 65 moved or readjusted.

What I claim as new, and desire to secure by Letters Patent, is—

1. The turning-tool holder consisting of the stock A, having an aperture crosswise near 70 its front end for the cutting-tool and an intercepting aperture lengthwise for a key and adjusting-bolt, sliding key C, having its front end adapted to fit into recesses on the rear of the cutting-tool, and adjusting-bolt D, provided 75 with a screw-thread working in a corresponding thread in the longitudinal aperture in the stock, and having a square head or equivalent means of turning said bolt, substantially as set forth.

2. The stock A, provided with sliding key C and adjusting-bolt D, in combination with cutting-tool B, having recesses c on its rear, and adapted to receive the front end of the key, substantially as described.

85 In testimony whereof I affix my signature in presence of two witnesses.

ALONZO PAWLING.
